UNITED STATES PATENT OFFICE.

JESSE B. BROWN, OF DETROIT, MICHIGAN.

INTERNAL-COMBUSTION ENGINE.

1,148,657.

Specification of Letters Patent. Patented Aug. 3, 1915.

Application filed February 3, 1913. Serial No. 745,928.

To all whom it may concern:

Be it known that I, JESSE B. BROWN, a citizen of the United States, residing at 243 Buena Vista street west, Detroit, Michigan, have invented certain new and useful Improvements in Internal-Combustion Engines, of which the following is a specification.

This invention relates to improvements in internal combustion engines.

The improvements relate particularly to an improved valve structure and mode of operating and controlling the same whereby the charge is so regulated by a rejection of the surplus that great economy of operation is secured and undue and unnecessary heating is so completely avoided as to avoid the necessity for a water jacket on engines of the size usually adopted for automobile use.

20 The objects of this invention are, first, to provide an improved structure of valve means which controls both the intake and exhaust, comprising both a sleeve and puppet valve; second, to provide a valve of the 25 class described associated with an improved valve controlling mechanism; third, to provide an improved regulable valve mechanism that effectively controls the intake whereby any surplus or excess charge will 30 be rejected and returned to the intake manifold; fourth, to provide an improved means for manually, or by automatic governor, controlling the intake valve of an internal combustion engine while the engine is in 35 motion.

Other and further objects relating to economies and details of operation and construction will definitely appear from the description to follow.

40 I accomplish the objects of my invention by the devices and means described in the following specification.

The invention is clearly defined and pointed out in the claims.

45 So much of an automobile engine as it is necessary to illustrate to show one preferred embodiment of my invention is fully illustrated in the accompanying drawing, constituting a part of this specification, in 50 which:

Figure I is an elevation view of the manifold side of a four cylinder engine showing only so much thereof as is needed to understand my improvement, the manifold itself being broken away and the carburetor, ignition and many other parts being omitted.

Fig. II is an enlarged detail sectional view on line 2—2 of Fig. III showing details of the valve means on one pair of cylinders, many parts appearing in full lines. Fig. 60 III is an enlarged detail sectional view taken on line 3—3 of Figs. I and II. Fig. IV is an enlarged detail sectional view of the cam shaft driving gears, taken on line 4—4 of Fig. II. Fig. V is an enlarged detail horizontal sectional view through the valve means, taken on a line corresponding to line 5—5 of Figs. II and III. Fig. VI is an enlarged detail sectional view taken on line 6—6 of Fig. II, showing details of the 70 sleeve valve connection to the cam shaft. Fig. VII is an enlarged detail sectional view taken on line 7—7 of Fig. II, showing details of the actuating cam means for the puppet valve to control the intake valve, 75 part of the valve stem being broken away and the control thrust bar being partly broken away. Fig. VIII is an enlarged detail plan view of the control thrust bar and its pivot. Fig. IX is a detail sectional 80 view on line 9—9 of Fig. III, showing the rock shaft connections for adjusting the said control thrust bar. Fig. X is an enlarged detail sectional view on line 10—10 of Fig. II, showing the relative form and 85 position of the cams 19 and 20 in their relation to the control thrust bar 18 and the shortened part 18' thereof.

In the drawing, the sectional views are taken looking in the direction of the little 90 arrows at the ends of the section lines, and similar numerals of reference refer to similar parts through the several views.

Considering the numbered parts of the drawings, the engine cylinders 1 are cast 95 in pairs with suitable cooling fins thereon. The crank casing 2, the engine pistons 3, the pitman 4, the crank shaft 5, the intake manifold and the exhaust pipe 7 are all of any usual or desired construction and need 100 no detailed description here, as my invention does not pertain to such details.

A puppet valve 8, with a stem 8', is supported in a central tubular bearing 9 in the valve casing 11 and rests in valve seats 10 105 at the top of such casing. The casing 11 is cast integral with the engine cylinder in each instance. An annular exhaust port 7' is toward the top of the casing and leads to the exhaust pipe, and an annular intake port 11c 6" is toward the bottom thereof and leads from the intake manifold 6 and passage 6'.

These annular ports are controlled by the sleeve valve 27 hereinafter to be described, which reciprocates in a cylindrical bore in said valve casing.

5 The cylinder head 12 is ribbed on the outer surface to facilitate cooling and is recessed to connect the cylinder to the valve ports.

10 The puppet valve 8 is controlled by connections to the cam of the cam shaft. The lower end of valve stem 8' is provided with flange 13 retained by cross pin 14 to receive the thrust of the valve spring 15, which forces the valve 8 tight into its seat. An adjusting screw 17 is threaded into the upper end of push rod 16. The push rod 16 rests upon the control thrust bar 18 above the cam 19 on the cam shaft 21.

15 The shortened and curved portion 18' of the control thrust bar coacts with the cam 20, and owing to its form, when shifted backward and forward, times the action of the puppet valve to vary the amount of the charge retained in the engine cylinder from 25 a full charge to such minimum amount as the character of the fuel or the particular duty of the engine seem to require. The relation of these parts clearly appears in Fig. X. The cam 19, by its action, opens the 30 intake valve and the cam 20 regulates the closing of the same by coacting with the shortened and specially formed part 18' of the control thrust bar 18. An important part of my invention is these coacting parts 35 18' and 20.

35 The sleeve valve 27 is controlled by a crank pin 21' on the cam shaft 21. A suitable guide pin 28 extends down from the valve and is secured to plunger 29 by cross 40 pin 30. (See Fig. VI). A hook or slotted part 31 carried by the lower end of plunger 29 permits of lateral motion of the crank pin 21', which reciprocates the valve stem 28 and the sleeve valve 27. The sleeve valve 27, when in its upper position, opens the intake part 6'' and the explosive charge can pass up through the center of the valve past the puppet valve when open. (See left hand valve of Fig. II.) The sleeve 27 in 45 this position closes the exhaust port 7' at the top. This permits the charge to be taken in. When the charge is taken in, the sleeve 27 descends after the puppet 8 closes under compression. When the 50 charge has been fired, the puppet 8 is raised by the cam and opened while the sleeve is in lowest position, and the exhaust then being open the burnt gases pass out of the exhaust and the engine scavenges.

55 The upper end of the sleeve valve 27 is thickened at 27' and fits the annular enlargement 28' at the upper end of central tubular guide 9 and secures a double closure of the intake while the exhaust occurs. This 60 is, of course, desirable in that the intake is

kept free of the foul gases, and undue heating is avoided.

The control thrust bar 18 is connected to pivot pin 23 on arm 24 on rock shaft 25 which is in suitable bearings in the crank case. An arm 26 is secured to the rock shaft to control the same, either manually or by suitable connections from some convenient part, as means on the steering column of an automobile.

70 Gears 32 and 33 are provided to drive the cam shaft from the crank shaft in the usual way. (See Figs. II and IV.)

75 The guides for the valve push rods are shown directly supported in the main casting. These guides can, of course, be supported in various ways by separate brackets not necessary here to illustrate.

80 The control thrust bar can be coupled to suitable governor means, making the regulation of the engine automatic. I prefer, however, the manual control of this part and have illustrated that part specifically in this application, and desire to claim the same specifically, as well as broadly.

85 I have described the valve 27 as a sleeve valve. It might also be described as a piston valve, and could readily be adapted to this use, although it was not made hollow, and in defining the same broadly and in these broad relations, I have referred to it as a piston valve. It is, of course, a sleeve piston valve. It does not matter whether the valves are controlled by cams or eccentrics on the cam shafts, or by what means 90 they are controlled in the broad essence of the invention.

95 My improvements are shown embodied in a four cycle engine, but they are readily adaptable to other styles. The valves can be differently designed and connected to do the work. I have shown a preferred form, which I wish to claim specifically in this case, along with broad claims to the generic structure, as will be seen by reference to the 100 appended claims.

Having thus described my invention, what I claim as new and desire to secure by Letters Patent is:

110 1. In an internal combustion engine, the combination of a puppet valve provided with a valve stem, a push rod adjustably secured to the end of said valve stem, a cam shaft, a pair of cams provided on said cam shaft, a control thrust bar interposed between said push rod and said cams said control bar having a longer portion engaging one of said cams and supporting the end of said push rod, and a shorter portion having a curved outer end engaging the other of 115 said cams, and means for actuating said control thrust bar, all coacting substantially as described for the purpose specified.

120 2. In an internal combustion engine, the combination of a puppet valve provided 125

with a valve stem, a cam shaft, a pair of cams provided on said cam shaft, a control thrust bar interposed between said valve stem and said cams said control bar having 5 a longer portion engaging one of said cams and supporting the end of said valve stem, and a shorter portion having a curved outer end engaging the other of said cams, and means for actuating said control thrust bar, 10 all coacting substantially as described for the purpose specified.

3. In an internal combustion engine, the combination of an intake valve provided with a valve stem, a cam shaft, a pair of 15 cams provided on said cam shaft, a control thrust bar interposed between said valve stem and said cams said control bar having a longer portion engaging one of said cams and supporting the end of said valve stem, 20 and a shorter portion engaging the other of said cams, and means for actuating said control thrust bar, all coacting substantially as described for the purpose specified.

4. In an internal combustion engine, the combination of a puppet valve, provided 25 with a valve stem; a cam shaft; a pair of cams provided thereon; a control thrust bar

supporting the lower end of said valve stem, and having portions in engagement with each of said cams; and means for reciprocating said control thrust bar to vary the time of closing of said puppet valve, all coacting substantially as described and for the purpose specified.

5. In an internal combustion engine, the combination with an engine cylinder and an intake manifold, of a valve controlling communication between said intake manifold and said cylinder, a cam shaft with cams thereon, means actuated by said cams for 40 opening said valve, and an adjustable slide means interposed between said cams and said valve for varying the time of closing said valve to permit the rejection of a varying portion of the charge into the intake manifold.

In witness whereof, I have hereunto set my hand and seal in the presence of two witnesses.
